UNITED STATES PATENT OFFICE.

ROSS W. HORN, OF BLADENSBURG, OHIO.

THILL-COUPLING.

SPECIFICATION forming part of Letters Patent No. 651,311, dated June 5, 1900.

Application filed March 24, 1900. Serial No. 10,058. (No model.)

To all whom it may concern:

Be it known that I, Ross W. HORN, a citizen of the United States, residing at Bladensburg, in the county of Knox and State of Ohio, have 5 invented a new and useful Thill-Coupling, of which the following is a specification.

The invention relates to improvements in thill-couplings.

One object of the present invention is to 10 improve the construction of thill-couplings and to provide a simple and comparatively inexpensive one which will be strong and durable and which will enable the operation of coupling and uncoupling to be rapidly 15 performed, so that a pole or a pair of thills may be easily connected to the running-gear of a vehicle.

-A further object of the invention is to provide a device which when changing poles and 20 thills will have no loose or separate pieces which must be placed upon the ground or other support while the change is being made from poles to thills, or vice versa.

Another object of the invention is to obviate 25 the necessity of employing an antirattler-spring to take up the wear.

The invention consists in the construction and novel combination and arrangement of parts hereinafter fully described, illustrated 30 in the accompanying drawings, and pointed out in the claims hereto appended.

In the drawings, Figure 1 is a perspective view of a thill-coupling constructed in accordance with this invention. Fig. 2 is a longitudinal sectional view, the thill-iron being 35 in position. Fig. 3 is a transverse sectional view of the same. Fig. 4 is a longitudinal sectional view, the thill-iron being removed. Fig. 5 is a detail perspective view of the levers, the spring, and the yoke. Fig. 6 is a detail perspective view of the thill-iron.

Like numerals of reference designate corresponding parts in all the figures of the drawings.

45 1 designates an axle-clip provided with a clip-plate 2 and having forwardly-extending ears 3, and the latter are provided with open bearings 4 for the reception of a coupling-pivot 5, which is rigid with a coupling or 50 thill iron 6. The bearings 4 incline upward and rearward slightly, and the pivot 5 projects laterally beyond the ears 3, and its ends

are engaged by a pair of levers 7, fulcrumed between their ends by bolts 8 or other suitable fastening devices on the arms 3, at the 55 outer faces thereof and at points in rear of the bearings 4. The upper arms of the levers 7 are provided with hooks 9, which engage over the ends of the pivot of the thill or coupling iron 6, as clearly illustrated in Fig. 60 1 of the accompanying drawings, whereby the thill or coupling iron is securely fastened to the axle-clip. The levers 7 are adapted to be swung to the position illustrated in Fig. 5 of the accompanying drawings to enable the 65 thill or coupling iron to be lifted out of the bearings of the axle-clip.

The lower arms of the levers 7 extend below the axle 10 and are provided at their inner faces with inwardly-extending rounded 70 studs 11, receiving coils 12 of a substantially U-shaped spring 13, which carries a yoke 14, the yoke 14 being adapted to engage an extension 15 of the clip-plate 2, whereby the spring is placed under tension and the levers 75 are yieldingly held in engagement with the pivot. The coils are located adjacent to the terminals 16 of the sides of the spring, and the said terminals 16 are bent outward and are secured within perforations 17 of the arms 80 of the levers 7, whereby the spring is connected with the same. The spring is swung rearward beneath the axle, and the yoke, which is provided at its ends with eyes 18 for the reception of the sides of the spring, is adapted 85 to engage notches 19, formed in the upper face of the extended portion of the clip-plate. The yoke when in engagement with the extended rear portion of the clip-plate is located at a point intermediate of the ends of the 90 sides of the spring, and the rear portion 20 is bent downward and forms a convenient handle to enable the yoke to be lifted out of engagement with the clip-plate. The spring operates to throw the upper arms of the levers forward and downward, and thereby maintains the pivot of the thill or coupling iron at the bottoms of the bearings, and it thereby takes up the wear and prevents rattling and obviates the necessity of employing 95 an antirattler device.

It will be seen that the thill-coupling is exceedingly simple and inexpensive in construction, that it possesses great strength and du-

rability, and that it is readily and quickly manipulated to enable it to be arranged in the positions illustrated in Figs. 1 and 5. It will also be apparent that it will enable poles 5 and thills to be readily changed and substituted for each other and that there are no loose parts of the coupling which become separated during the operation of coupling and uncoupling.

10. What is claimed is—

1. A device of the class described comprising an axle-clip having open bearings, a coupling-iron having a pivot arranged in the bearings, a pair of levers fulcrumed between their 15 ends on the axle-clip in rear of the bearings and having upper hook-shaped arms and lower depending arms extending below the bearings, the upper hook-shaped arms engaging the pivot and retaining the same in the 20 bearings, and a spring connected with the lower arms of the levers and with the axle-clip, and located beneath the latter, substantially as and for the purpose described.
2. A device of the class described comprising 25 an axle-clip having open bearings, a coupling-iron having a pivot arranged in the bearings, a pair of levers fulcrumed on the axle-clip and provided with upper hooks for engaging the pivot and having depending arms, 30 studs extending from the depending arms, a spring having coils disposed on the studs, and means for connecting the spring with the axle-clip, substantially as described.
3. A device of the class described comprising

ing an axle-clip having open bearings and provided with a rearwardly-extending clip-plate 35 provided with recesses at its upper face, a coupling-iron having a pivot arranged in the open bearings, a pair of levers fulcrumed on the axle-clip and engaging the pivot to retain 40 the same in the bearings, said levers having arms depending below the axle, a spring connected with the depending arms of the levers, and a yoke loosely connected with the spring 45 and detachably engaging the extended portion of the clip-plate, substantially as described.

4. A device of the class described comprising an axle-clip having forwardly-projecting ears provided with open bearings, a coupling-iron having a pivot arranged in the bearings, 50 a pair of levers fulcrumed on the exterior of the ears in rear of the bearings and provided with upper hooks and depending arms, studs extending from the depending arms, a spring 55 provided with coils arranged on the studs, said spring having its terminals extended beyond the coils and secured to the levers, and a yoke connected with the spring and adapted to engage the clip-plate of the axle-clip, substantially as described.

In testimony that I claim the foregoing as my own I have hereto affixed my signature in the presence of two witnesses.

ROSS W. HORN.
